UNITED STATES PATENT OFFICE.

IRVING PHILLIP MILLER AND LAWRENCE MONROE RAKESTRAW, OF TOLEDO, OHIO,
ASSIGNORS TO WM. M. HOGLE AND LACEY Y. WILLIAMS, OF TOLEDO, OHIO.

GAS-ENGINE CASING OR FRAME.

No. 878,466.

Specification of Letters Patent.

Patented Feb. 4, 1908.

Application filed February 4, 1907. Serial No. 355,612.

To all whom it may concern:

Be it known that we, IRVING PHILLIP MILLER and LAWRENCE MONROE RAKESTRAW, citizens of the United States, residing at Toledo, in the county of Lucas and State of Ohio, have invented new and useful Improvements in Gas-Engine Casings or Frames, of which the following is a specification.

10 Our invention relates to explosive gas engines, and especially to the construction of the casting or frame, the object being to obviate the use of cores as far as possible in casting the frame and in forming spaces to 15 receive the water which circulates about the cylinder, and the exhaust gases.

These objects are readily accomplished by casting the casing with two flat sides, opposite each other, and with openings for the 20 water, exhaust, and compression and crank-chambers, and then securing to each flat side a plate to form said chambers complete.

Other objects of the invention will become apparent upon a full disclosure thereof.

25 By making two of the sides flat, the casting can be done by employing a split or sectional pattern, which will permit of each section being withdrawn from opposite sides.

In the drawings—Figure 1 is a vertical section of our improved engine casing; Fig. 2, a section, partly broken away, on line $x-x$ of Fig. 1; Fig. 3, a section on line $y-y$ of said Fig. 1; Fig. 4, an inner face view of one of the side plates; Fig. 5, a side view of one of 35 the crank-shaft bearings; Figs. 6 and 7, bottom and top plan views, respectively, of the engine casing, showing the side plates attached, and Fig. 8 a view in elevation of the exhaust side of the casing.

40 Referring to the several views, the numeral 1 indicates the casting forming the main portion of the engine casing, and the same is provided with the piston cylinder 2, and lower compression and crank-shaft 45 chamber 3. In making the casting open spaces 4 and 5 are provided to form part of a water chamber or jacket around the piston-cylinder, and an open space 6 to provide part of an exhaust-chamber. The compression and crank-shaft chamber is cast integral with the water-jacketed cylinder, the cylinder end of the casting being substantially square. These are important features of our invention, and tend materially to lessen the cost

and simplify the construction of this type 55 of engine.

By making the casting with two vertical parallel sides, openings for the water, exhaust, and lower compression-chambers are formed by using a split or sectional pattern, 60 which permits of each section being drawn away from opposite sides, casting being accomplished by the ordinary method of making common castings. The casting is provided with the usual openings for the mixing- 65 valve, spark-plug, and exhaust-pipe, as indicated by numerals 7, 8, and 9, respectively, and with the usual inlet port 10 and exhaust-port 11.

To each parallel side of the casting is 70 firmly secured, by bolts 12, plates 13; a suitable packing 14, preferably asbestos and shellac, being employed between the joints, as shown in Fig. 8. Each plate is provided with an opening 15 and a bearing 16, cast 75 integral with the plate, for the reception of the crank-shaft 17, and one of said plates is provided with a water-inlet 18.

The water-chamber is provided with a water-pipe or duct 19, through which the 80 overflow water is conducted to the exhaust-chamber 6. This pipe is cast integral with the water-jacket cylinder, as shown in Fig. 1.

Having fully described our invention what we claim, is—

1. The combination with an integral casting for a gas engine having an open space 3 at one end for a crank chamber, a space 6 for exhaust gases, and spaces 4 and 5 for water, of two plates each of the length of the casting applied to opposite sides of the same and closing the said spaces so as to form inclosed crank, water, and exhaust-gas chambers.

2. The combination with an integral casting for a gas engine having a cylindrical opening 2 at one end to receive a piston, a space 3 at the opposite end for a crank chamber, spaces 4 and 5 to receive water, and a space 6 for exhaust gases, said spaces being formed by the walls of the casting, of side plates secured to the two open sides of the casting, said plates entirely closing the crank chamber space 3, and forming with the spaces 4 and 5 and space 6 an inclosed water space and an inclosed space for exhaust 105 gases outside the cylindrical opening for the piston.

3. The combination with an integral cast-

ing for a gas engine having two of its opposite sides lying in substantially parallel planes, a longitudinal cylinder opening at one end, spaces for water and exhaust gases adjacent to the cylinder opening, and a space for a crank chamber at the other end, of two plates, one secured to each of the said opposite sides of the casting and entirely closing the spaces for the water, exhaust gases and the crank, whereby inclosed spaces for water, exhaust gases and a crank are formed.

4. The combination with a casting for a gas engine having two of its sides in parallel planes extending from end to end of the

casting, with open spaces bounded by the 15 walls, of two plates of the same length as the casting and removably secured to said two parallel sides of the casting and closing said open spaces so as to form inclosed spaces for water and a crank.

In testimony whereof we affix our signatures in presence of two witnesses

IRVING PHILLIP MILLER.
LAWRENCE MONROE RAKESTRAW.
